UNITED STATES PATENT OFFICE.

LENORA H. JONES, OF WICHITA, KANSAS.

ELECTRIC TALKING-SIGN.

1,143,201.

Specification of Letters Patent. Patented June 15, 1915.

Application filed April 14, 1914. Serial No. 831,850.

To all whom it may concern:

Be it known that I, LENORA H. JONES, a citizen of the United States, residing at Wichita, in the county of Sedgwick and 5 State of Kansas, have invented certain new and useful Improvements in Electric Talking-Signs, of which the following is a specification.

This invention relates to what are popularly known as talking signs, that is to say, a bank of electric lamps which can be lighted in groups in such a manner as to form letters, words, emblems, pictures and the like, and can be varied at a more or less 15 rapid rate so as to produce a series of effects designed to convey any desired information to the observer.

The object of my invention is to simplify the construction and increase the range of 20 such a sign, and render it possible to make changes easily and quickly in the words or other devices used to attract the attention of the public.

To this end, my invention comprises a 25 bank of electric lamps arranged in rows close together and connected with a peculiar switching apparatus by means of which any desired group or groups of lamps can be lighted in succession; the essential novelty 30 residing in said switching apparatus. In brief, this consists of a set of adjustable contacts for each lamp, connected in series, combined with a contact movable relatively thereto, and means for causing said latter 35 contact to shift from one contact to another in order and preferably at regular intervals. Each of the contacts in each set can be thrown into operative position or out of it at will, so that any given lamp can be 40 lighted at any one or more of the successive positions of the movable contact. The number of changes of which the sign is capable will thus depend simply upon the 45 number of such contacts with which each lamp is provided.

On the accompanying drawings, Figure 1 is a diagrammatic representation of the entire sign. Fig. 2 is a plan view, on a larger scale, of the mechanism for producing the 50 step by step movement of the movable contact carrier. Fig. 3 is a plan view of said carrier on another scale. Fig. 4 is a section on a large scale of a portion of the table, carrier and its actuating mechanism. Fig. 55 5 is a plan view, partly broken away, of a portion of the table and the carrier. Fig. 6

shows a modified form of stationary contact, and Fig. 7 shows a further modification of the same.

The drawings represent the preferred 60 form of my invention, but it will be evident from the following detailed description that the actual construction can be widely varied without departing from the scope and spirit of said invention.

65 Mounted upon some convenient support is a bank of electric incandescent lamps 1, preferably arranged in regular rows. The number of lamps used is immaterial, provided enough are employed to afford the 70 requisite changes in displaying the selected legends or designs.

75 One terminal of each lamp is connected by a common conductor 2 with one side of a supply circuit 3. The other terminal of 80 each lamp is connected by a separate conductor 4 with the switching apparatus. In the form which I have illustrated, each of these separate conductors terminates in a loop 5 surrounding a circular hole 6 in a stationary table 7, which is preferably horizontal. The holes are arranged in rows corresponding with the lamps in the bank on the display support, so that each hole in each 85 row agrees in relative position with its lamp 90 in the bank. A plurality of adjustable contacts is arranged around each hole, all connected with the loop of conductor 5, and all spaced at equal distances apart. In the drawings I have shown eight of these contacts, but the number can obviously be 95 varied at the pleasure of the designer. The simplest form of contact is that of a disk 8 centrally perforated and rotatable upon an upright pin 9 whose base is electrically connected to the loop 5. The operator in control of the sign must have a supply of these disks, enough to equip as many of the pins as may ever be needed.

100 Underneath the table 7 is a movable board or carrier 10 upon which are mounted upright contacts 11 projecting up through the holes in the table, one for each hole. The preferred form of movable contact is a 105 closely coiled flexible helical spring of copper or other wire, whose base is anchored to the board. A convenient way of mounting these springs is to slip them down over upright studs 12 fixed in the board. The studs are all electrically connected, preferably by strips 13 of copper or other conducting material. A common flexible conductor 110

14 connects all these strips and contacts with the other side of the supply circuit, as shown. A circuit-controlling switch 15 of ordinary construction is preferably included 5 in circuit with the two conductors 2 and 14. It will be seen that when a movable contact 11 is brought against a contact 8 the circuit of the corresponding lamp will be closed and said lamp will light.

10 In order to be able to light any particular lamp as often as may be necessary in forming the words or other designs to be displayed, provision is made for causing the movable contacts to travel around the outer 15 portion of the holes 6 with a step by step motion, each step carrying the movable contact from one stationary contact to the next. By simply removing one or more of the disks 8 from their pins, the lamp in circuit 20 with that particular set of contacts will be prevented from lighting at the positions of the movable contact corresponding with the removed disks. The operator can thus determine beforehand whether or not any particular lamp shall light up at any given 25 position of the movable contacts in their travel around within the holes.

Various equivalents for the removable disks may be substituted therefor, such for 30 example as a light helical spring 16 clamped at one end by a nut 17 or otherwise so mounted as to permit it to be swung into or out of the path of the movable contact 11, as shown in Fig. 6. Or, a flat spring blade 18 35 may be similarly mounted, as shown in Fig. 7.

In order to carry the movable contacts 11 around in circular paths within their respective holes 6, the board 10 on which said 40 contacts are mounted is supported in such manner as to be capable of revolution without rotation. To this end it is preferably provided with ball casters 19 resting upon a base plate 20 which is parallel with the table 45 7. Rotatably mounted on upright axes, such as studs 21 rising from said base plate, are two wheels 22 having wrist pins 23 projecting from their upper surfaces and entering sockets 24 in the board 10. The throw 50 of these wrist pins is such that when the wheels are revolved every point in the board will be given a circular movement of rotation in a circle whose diameter is slightly less than that of one of the holes 6; the motion 55 of the board as a whole being similar to that of the side rod of a locomotive with reference to the axles of the driving wheels.

The board is moved with a step by step movement, preferably by the following 60 mechanism. On the under side of the wheels 22 is a plurality of teeth or cogs 25, spaced equally apart and corresponding in number to the stationary contacts 8. A rod 65 26 is mounted to reciprocate in suitable guides 27 on the base plate and is provided

with pawls or dogs 28 adapted to engage with said cogs when the rod moves in one direction and to slip back past them when the rod returns. The pawls are pivoted to the rod and are provided with springs 29 70 which throw them into the path of the cogs but permit them to yield and slip over said cogs when the rod is retracted. At each reciprocation of the rod, both wheels will be advanced a portion of a revolution, remaining stationary while the rod makes its backward stroke. A detent, such as the flat spring 30 bearing against two of the cogs, prevents any back lash of the wheels.

Any suitable mechanical device may be 80 used to reciprocate the rod. I prefer to employ a small electric motor 31, connected by reducing gearing and a crank pin 32 and pitman 33 with one end of said rod. The motor may be connected with the supply circuit 85 3 and be controlled by a switch 34.

At each reciprocation of the rod 26 the movable contacts 11 are shifted from one position to the next within their holes, all occupying corresponding positions. The 90 operator selects the lamps to be lighted at each position of said contacts, and adjusts the stationary contacts to cause their circuits to be closed as desired; for example, by dropping one of the disks 8 upon each 95 pin 9 so selected, or by turning the contact 16 or 18 into the path of the movable contact, and clamping it in position. When this has been done, the motor can be started and the sign will display as many words or 100 designs as are provided for by the stationary contacts in circuit at each position of the movable contacts; repeating the announcement at each revolution of the board 10.

It will be seen that this sign possesses a 105 great range of "conversational ability", so to speak, and that what it says can be very easily and quickly altered by simply shifting the movable contacts.

In accordance with the provisions of the 110 patent statutes, I have described the principle of operation of my invention together with the apparatus which I consider to represent the best embodiment thereof; but I desire to have it understood that the apparatus shown is only illustrative, and that the invention can be carried out by other means.

What I claim is:

1. The combination with a bank of electric lamps, of switching apparatus for lighting groups of lamps at will, comprising sets of contacts, the contacts of each set connected in series and in circuit with its own lamp, a single contact coöperating with 120 those in a set, and means for effecting relative movement of each set and its single contact, whereby all said single contacts will coöperate in succession with the contacts in the several sets. 125

2. The combination with a bank of electric lamps, of switching apparatus for lighting groups of lamps at will, comprising a set of contacts for each lamp, the contacts of each set connected in series, a single contact moving relatively to those in said set, and means for bringing any one or more of the set into or out of the path of movement of said single contact. 5
- 10 3. The combination with a bank of electric lamps, of switching apparatus for lighting groups of lamps at will, comprising sets of contacts, the contacts of each set connected in series with each other and with a lamp and arranged in a loop, a single movable contact in each loop, and means for moving said single contacts from one contact to the next in succession in their several sets. 15
- 20 4. The combination with a bank of electric lamps, of switching apparatus for lighting groups of lamps at will, comprising sets of contacts, the contacts of each set connected in series with each other and with a lamp and arranged in a loop, a single movable contact in each loop, means for moving it from one contact to the next in succession, and means for removing any one or more of the contacts of each set from the path of the 25 moving contact. 30
5. The combination with a bank of electric lamps, of switching apparatus for lighting groups of lamps at will, comprising sets of contacts, the contacts of each set connected in series with each other and with a lamp and arranged in a loop, a single movable contact inside of each loop, a board on which said single contacts are mounted, and means for giving said board a movement of 35 40 revolution without rotation.
6. The combination with a bank of electric lamps, of switching apparatus for lighting groups of lamps at will, comprising sets of contacts, the contacts of each set connected in series with each other and with a lamp arranged in a loop, a single flexible movable contact inside of each loop, a board 45
- on which said single contacts are mounted, rotatable wheels having wrist pins engaging with said board, and means for actuating said wheels. 50
7. The combination with a bank of electric lamps, of switching apparatus for lighting groups of lamps at will, comprising a table containing circular holes, a set of contacts grouped around each hole at equal distances, contacts projecting through said holes, means for moving said last named contacts in circular paths within said holes, and means for giving them a step by step motion, their positions of rest corresponding with the contacts grouped around said holes. 55
8. The combination with a bank of electric lamps, of switching apparatus for lighting groups of lamps at will, comprising a table containing circular holes, a set of contacts grouped around each hole at equal distances, contacts projecting through said holes, a board parallel with said table on which said last named contacts are mounted, 60 and means for giving said board a movement of revolution without rotation. 65
9. In a sign of the class described, a table having a plurality of circular holes, a set of pins around each hole connected in series, a removable disk on each pin, a contact inside of each hole, and means for giving it a step by step motion from one pin to the next. 70
10. In a sign of the class described, a table having a plurality of circular holes, a set of pins around each hole connected in series, a removable disk on each pin, a board parallel with said table, a plurality of electrically connected studs on said board, one for each hole, and helical springs carried by said studs and extending up through said holes. 80
